CLAIM

The ornamental design for a micro-titration vessel, as shown and described.

DESCRIPTION

FIG. 1 is a front and right perspective view of a first embodiment of a micro-titration vessel;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a cross-sectional view thereof taken along the lines **8-8** of FIG. 2;

FIG. 9 is a front and right perspective view of a second embodiment of a micro-titration vessel;

FIG. 10 is a front view thereof;

FIG. 11 is a rear view thereof;

FIG. 12 is a left view thereof;

FIG. 13 is a right view thereof;

FIG. 14 is a top view thereof;

FIG. 15 is a bottom view thereof;

FIG. 16 is a cross-sectional view thereof taken along the lines **16-16** of FIG. 10;

FIG. 17 is a front and right perspective view of a third embodiment of a micro-titration vessel;

FIG. 18 is a front view thereof;

FIG. 19 is a rear view thereof;

FIG. 20 is a left view thereof;

FIG. 21 is a right view thereof;

FIG. 22 is a top view thereof;

FIG. 23 is a bottom view thereof; and,

FIG. 24 is a cross-sectional view thereof taken along the lines **23-23** of FIG. 18.
